UNITED STATES PATENT OFFICE.

OSWALD LEVER AND WILLIAM S. GRUNDY, OF PHILADELPHIA,
PENNSYLVANIA.

COP AND BOBBIN WINDING MECHANISM.

SPECIFICATION forming part of Letters Patent No. 503,325, dated August 15, 1893.

Application filed May 12, 1892. Serial No. 432,715. (No model.)

To all whom it may concern:

Be it known that we, OSWALD LEVER and WILLIAM S. GRUNDY, citizens of the United States, and residents of the city of Philadelphia, in the State of Pennsylvania, have jointly invented certain new and useful Improvements in Cop and Bobbin Winding Mechanism, of which the following is a full, clear, and exact description, reference being had to the accompanying drawings, forming a part of this specification.

Our invention relates to cop and bobbin winding mechanism, and consists, first, in the combination with sets or groups of vertically arranged spindles and their actuating gearing, of driving devices adapted to directly gear with and simultaneously actuate each member of each set or group separately but with uniformity and precision; second, in the supporting and actuating devices driving and operating the vertical spindles; third, in the combination therewith, and with the frame of the machine, of the stop mechanism operating on the breaking of a thread to disengage the driving gear of the particular spindle carrying such thread; and finally of the combination and arrangement with the yarn guides, their actuating devices, the frame supporting the same, and the rotating spindles, of the yarn-supplying devices and the mechanism for supporting and adjusting the same.

In the accompanying drawings illustrating our invention, Figure 1 is a side view of two sets, each consisting of four vertical spindles, mounted in their actuating devices; the single driving shaft for the same; the yarn guides; and the cop forming mechanism. Fig. 2 is a horizontal sectional view of part of the same, through the line 9, 10, of Fig. 10, showing the arrangement of the spindles and their actuating devices, in groups or sets, and the driving gearing for the same, set in the frame of the machine. Figs. 3, 4 and 5 are views of the cop forming device and of the mechanism for stopping the rotation of a spindle on the breaking of its thread; shown in its two positions. Fig. 6 is a vertical sectional view of the supporting and actuating device for the spindle. Fig. 7 is a section through the line 1—2 of Fig. 6. Fig. 8 is a section through the line 3—4 of Fig. 6. Fig. 9 is a section through

the line 5—6 of Fig. 6. Fig. 10 is a vertical sectional view through the line 7—8 of Fig. 1. Fig. 11 is a right hand side view of Fig. 1. Fig. 12 is an elevation showing the upper portion of the frame supporting the upper and lower yarn guides and their shafts; the cop forming devices and their supporting rails, and the mechanism of the yarn supplying reels. Fig. 13 is a section through the line x—x of Fig. 12.

Mounted in the frame of the machine consisting of the uprights A and cross pieces A', is a horizontal driving shaft B, actuated by a pulley B'; and extending through the frame and carrying an eccentric B² to which is connected a strap B³, and a rod B⁴. The eccentric B² actuates the strap B³ which drives the yarn guide C²². The same eccentric carries the rod B⁴ for the purpose hereinafter mentioned. Upon said shaft B are mounted two bevel gears C', each meshing with inner bevel gear C on the face of a cog C² mounted on the cross pieces A' of the frame. This cog C² gears with cog wheels D supported indirectly by brackets D', (see Figs. 2 and 10) secured to the frame. These brackets (see Figs. 6 and 10) support the spindle driving bearings. The cogs D and their brackets are so arranged in groups or sets in the frame on the opposite side-rails A¹² that their peripheries will all mesh with the cog gearing on the periphery of the central cog C², which in turn is driven as aforesaid by the main driving shaft B. Secured to or made integral with the brackets D' are sleeves A⁹ which support the tubular shafts A⁸ carrying the spindles. The said side-rails A¹² A¹² each support a series of projecting spool supports A² upon which are mounted the spools A³. They also support the said spindle bearings hereinafter more particularly described and shown in detail in cross section in Fig. 6.

Mounted on each of the uprights A of the frame are supports A⁴, carrying the guide rod c'. On each of said uprights A is also mounted a vertical arm A⁵ in which a shaft K is journaled, said shaft actuating the several yarn-guides C¹² in the series and which shaft is vibrated by the strap B³. At the upper part of said vertical arm A⁵ is also mounted the usual tension device c³. The rod B⁴

(see Fig. 11) imparts a lateral reciprocating movement to the shaft X through a bell-crank lever X', (see Fig. 1,) the said shaft X carrying the lower yarn guide c and its stop pin B¹⁵, which operates as hereinafter described. An extension A²⁰ of the upright A (shown in Fig. 12) is provided to support the yarn reel E which is mounted on the end of an arm E' the other end of which is pivoted 10 at e in a double frame E² E³ which is slotted in an arc of a circle on each side at E⁴ E⁴ terminating in a recess e'. The yarn reel arm E' has an operating handle E⁵ affixed to it, and a projecting pin e², the latter adapted to fit in the slot E and recess e'. This construction enables the yarn reel to be raised and lowered in an arc of a circle by grasping the operating handle of its supporting arm, and when raised the reel is adjustably locked in 20 position by the pin e² resting in the recess e' of the slot E⁴. The double frame E² E³ supports a similar yarn reel and operating mechanism, on each side.

The spindle A⁷ (see Figs. 6 and 10) is square at its lower end and rests in a square journal (see Figs. 7, 8 and 9) in the tubular shaft A⁸ which rests in and upon the sleeve A⁹ which is secured to or made integral with the bracket D'. The shaft A⁸ is recessed on its under 30 end at b to receive the pin A¹⁰ fixed on the face of the cog D. Said cog is maintained in proper lateral position, indirectly by the brackets D' (see Fig. 2) supporting the sleeve A⁹ and its contained tubular shaft A⁸ (see Fig. 10) and actuates the spindles A⁷ mounted in the tubular shaft A⁸, and the said cog D carries on its under face a collar F' which has its bearing in a pronged arm F on the base of the spring rod A⁶ carrying the stop 40 mechanism hereinafter described. By means of this spring rod the said actuating cog D is thus adjustably maintained vertically. The spring g encircles the rod A⁶ between the said prong F and an extension b' of the sleeve A⁹ and tends to withdraw the pins A¹⁰ of the cog D from the recesses b in the shaft A⁸ when the rod A⁶ is no longer held up by the stop mechanism B⁵ hereinafter described. Said stop mechanism is shown in normal position 50 in Fig. 4.

The cop forming cup H is constructed integral with its supporting bracket H' and H², and is secured through the bolt hole H³ to the supporting rail H⁴ provided therefor (see Fig. 5 10). The rod A⁶ passes through a recess in the base H² of the cup supporting bracket and above and resting on the same are secured thereto devices (shown in detail in Figs. 3, 4 and 5 and in connection with the tension 55 devices in Fig. 10), for throwing the spindle out of gear when a thread breaks. These devices consist of a short cam B⁵ provided with a handle D², and pivoted in a recess on the end of a bar screwed to the top end of the 60 rod A⁶. This cam is shown in normal position in Fig. 4, holding up the rod A⁶, and keeping the driving cog D in register with

the tubular shaft A⁸. In Fig. 3 it is shown thrown down, whereby the rod A⁶ is released and the driving cog D thrown out of register 70 with the tubular shaft A. This is accomplished on the breaking of a thread, by means of the stop pin B¹⁵ which is mounted loosely on the shaft X and in this stop pin is fastened by a set screw, the end of the yarn 75 guide c so that when the thread breaks the yarn guide drops (as shown in Fig. 10), its stop pin striking against and upsetting the cam B⁵ releasing the spring controlled rod A⁶. A handle D² on the cam enables it to be restored to normal position. The yarn guide c with its stop pin B¹⁵ is journaled on the shaft X, and this journal bearing, while free to rotate on the shaft X is fixed against longitudinal movement thereon, by means 85 of collars, pins, or other equivalent devices. The shaft X has a lateral reciprocatory movement of a fraction of an inch produced by the strap B⁴ actuating it through the bell crank lever X' (see Fig. 1). On the breaking 90 of the yarn, the yarn guide c will fall (as shown by dotted lines Fig. 10) thus carrying its stop pin B¹⁵ forward in line with the cam B⁵. The shaft X having a lateral reciprocatory movement, as before mentioned, 95 will carry the stop pin of the yarn guide mounted thereon, into contact with the cam and upset it (as shown in Fig. 3) and thus release the spring controlled rod A⁶ and disconnect the gear D with the driving shaft of the 100 spindle as before mentioned. The parts are restored to their normal position by re-threading the yarn guide, and raising the pivoted cam B⁵ by means of its handle D² (see Figs. 5 and 11). The arms A⁴ are projecting stationary posts on either side of the frame and support the guide post c (see Fig. 1) which directs the course of the several strands of yarn from the series of spools A³ to the wheels on the 105 end of the several yarn guides c. 110

The operation of the device is as follows:— Power being applied to the shaft B through the pulley B', the horizontal cog C² drives the several cogs D in the group or series with which it is geared, separately but directly and with uniformity and at a minimum of expenditure of power; and the stoppage of the separate driving gear of any spindle in the group will not effect the continued operation of the remaining spindles in the group. Two or more of such groups or sets, of preferably four spindles each, may be thus mounted and driven from a single shaft; and the same shaft, by means of the eccentric B² and its strap B³ fixed upon one of its ends, will, with equal 115 uniformity and precision, operate the several yarn guides for each spindle in each of the several groups or series of spindles through the shaft K and in unison with the mechanism actuating the spindles. 120

Yarn may be supplied from the small spools A³ (see Fig. 1) but preferably from and by means of our improved yarn supplying devices shown in Fig. 12. The spindles are 125 130

driven as described and form cops of yarn thereon, by means of the cop-forming devices in the usual manner.

Having thus described our invention, what we claim as new, and desire to secure by Letters Patent, is—

1. The combination with the supporting frame A, A', A¹², the horizontal driving shaft B, its gearing C', horizontal cog gearing C, C² driven thereby, a series of horizontal cogs D actuating cop and bobbin forming spindles arranged to be driven directly and uniformly from said central driving gear C², and devices secured to the frame adapted to separately support and maintain each of said actuating cog gears D in register with the central driving gear C²; substantially as described.

2. The combination with the vertical cop winding spindle, its actuating shaft A⁸, recessed on its under face at b, the supporting sleeve A⁹ in which it is mounted, the horizontal cog wheel D with the pin A¹⁰ on its upper face, the collar F', the prong F, the spring controlled rod A⁶ mounted therein, and mechanism mounted on said rod A⁶ operating to release the rod and thereby stop the rotation of the spindle when a thread breaks, by dropping the pins 10 on the face of the cog D out of register with the recesses in the tubular shaft A⁸; substantially as described.

3. In combination, a vertically mounted cop winding spindle and its tubular driving shaft,

actuating devices adapted to gear with said shaft, a spring controlled rod supporting said actuating devices, a cop forming device provided with a recessed supporting arm through which said spring controlled rod may pass, a cam resting on said supporting arm of the cop forming device and pivoted to the end of the spring controlled rod, and a yarn guide with the reciprocating shaft on which it is mounted, said guide carrying a stop pin adapted to contact with said cam and upset it on the breaking of a thread and release the spring controlled rod; substantially as described. 45

4. The combination with the supporting frame A its extension A²⁰, and with cop-winding mechanism, of yarn supplying devices consisting of a reel E, mounted upon a pivoted arm E', a lever E⁵ provided with a locking pin 50 e², a frame E² slotted at E⁴ in an arc of a circle and recessed at its upper extremity at e' to receive said locking pin and support the reel in an upright position; substantially as described.

In testimony whereof we have hereunto affixed our signatures this 18th day of November, A. D. 1891.
